UNITED STATES PATENT OFFICE.

JOSEPH HYMAN, OF NEW YORK, N. Y.

SETTING FOR JEWELRY.

Application filed February 10, 1921. Serial No. 443,758.

To all whom it may concern:

Be it known that I, JOSEPH HYMAN, a citizen of the United States, and resident of the borough of Manhattan, city, county, and 5 State of New York, have invented certain new and useful Improvements in a Setting for Jewelry, of which the following is a specification.

The invention relates to an improved setting for jewelry and has for its primary object to provide, as an article of manufacture a setting for rings in the form of an engraved or enamelled emblem or insignia. Heretofore, it has been the practice in the 10 manufacture of finger rings of this type, to engrave the emblem or insignia directly in the surface of the ring and then fill in the recesses resulting from the cutting or engraving with enamel until all of the 15 surfaces are flush, any projecting portion of the design or emblem being filed down. It was therefore necessary for the jeweller to carry in stock a large number of rings of different design. By means of my present invention, a relatively small number of ring 20 styles or designs may be kept in stock, and any desired insignia or emblem readily set into a ring selected by the purchaser.

It is also an object of my present invention to provide a setting for rings of the 25 above character which is simple and inexpensive in its construction and as attractive in appearance as the ordinary ring of this type wherein the insignia or emblem is engraved directly in the metal of the ring.

With the above and other objects in view, the invention consists in the improved form, construction and relative arrangement of the several parts as will be hereinafter more 30 fully described, illustrated in the accompanying drawing and subsequently incorporated in the subjoined claims.

In the drawing wherein I have illustrated one practical embodiment of the invention 35 and in which similar reference characters designate corresponding parts throughout the several views:

Figure 1 is a plan view showing a finger ring having my improved setting secured 40 therein.

Figure 2 is an edge view of the ring set.

Figure 3 is a sectional view thereof, and

Figure 4 is a plan view of the backing plate for the ring set.

55 Referring in detail to the drawing 5 designates a finger ring having an opening

therein to receive the improved ring set generally indicated at 6. Any approved means may be employed for securely fastening the set 6 in the ring, but as this fastening or 60 attaching means constitutes no part of the present improvement, it will not be herein described in detail.

The ring set, as constructed in accordance with one embodiment of my invention, includes a backing plate 7 which is of shallow dished form and is pressed by means of suitable dies to provide a multiplicity of facets 8 in simulation of a stone ring set.

The top plate 9 of the set has its front 70 face engraved or cut out to produce the insignia or emblem 9 in relief thereon. The spaces or recesses are filled in with enamel or other desired contrasting material as shown at 10 and any projecting portion of 75 the insignia or emblem is filed down until all surfaces are perfectly flush.

After the top plate has thus been provided with the insignia or emblem, it is arranged upon the edges of the backing plate 7 and 80 said edges of the backing plate and the edges of the top plate are securely welded together so as to produce in effect a one piece unitary structure. The finished commercial article in this form is sold to the jewelry trade. It 85 is apparent, of course, that the ring sets may be produced in different forms, shapes and sizes so that they can be attached or secured by the jeweller in rings of different sizes and designs. Thus the jeweller can readily provide upon demand a desired design or insignia in a ring of any selected shape or size. The ring sets may be readily produced from 90 gold, silver or other metal.

I have above referred to the ring set as 95 having a faceted backing plate, but it is to be understood that the invention is not necessarily limited to this particular form of the backing plate, as it might as well be produced in a plain rectangular shape and without the numerous facets. However, as the faceted backing plate improves the attractive appearance of the setting, I prefer to employ this construction.

From the foregoing description considered in connection with the accompanying drawing, the construction and several advantages of my improved ring set will be clearly understood. The two part construction of the ring set renders its manufacture 100 a relatively simple matter, and also enables the device to be produced with the use of a 110

comparatively small amount of metal so that the cost of material is reduced to a minimum. Instead of engraving the insignia or emblem in relief as above explained, it might 5 be set into the top plate in enamel or other material. It is also possible to vary the form, construction and arrangement of the several parts as occasion may demand, and it is accordingly to be understood that I reserve 10 the privilege of resorting to all such legitimate changes in the detail features of the device as may be fairly embodied within the spirit and scope of the invention as claimed.

I claim:

- 15 1. A metallic design carrying device adapted to simulate a stone having a faceted back plate, and a front design carrying plate secured to the edges of the faceted back plate.
2. A metallic design holder adapted to 20 simulate a stone and constructed for placement in a stone setting comprising a back

plate having facets to simulate a precious stone, and a front design carrying plate having its edges lying against the marginal edges of the back plate and being secured 25 thereto, the meeting edges of said front and back plates adapted to be received in a stone setting.

3. As an improved article of manufacture, a setting for emblem rings consisting of a 30 shallow dished backing plate and a top plate having an emblem on its front face and all surfaces of said emblem and the face of said plate disposed in a common plane, the marginal edges of said top plate 35 being secured to the marginal edges of the backing plate.

In testimony that I claim the foregoing as my invention, have signed my name hereunder.

JOSEPH HYMAN.
